UNITED STATES PATENT OFFICE.

AUSTIN L. MOORE, OF UNIONTOWN, PENNSYLVANIA, ASSIGNOR TO EUREKA FIRE BRICK WORKS, OF PITTSBURGH, PENNSYLVANIA, A CORPORATION OF PENNSYLVANIA.

DIE STRUCTURE FOR THE MANUFACTURE OF HOT TOPS.

Application filed August 19, 1927. Serial No. 214,090.

This invention relates to an improvement in the manufacture of hot tops for ingot molds.

The hot tops are composed of heat resisting material, such as fire brick, fire clay, and other cementitious substances, which are molded into the desired shape when the same is plastic. The purpose of this invention is to simplify the forming operation in order 10 that the hot tops may be made more economically. Machine presses are used in the manufacture of somewhat similar articles, such as seggars. The presses have an outer die within which the plastic substance to be formed is 15 placed. Arranged to move into the outer, or female forming die, is a plunger, or male die, which is forced down into the plastic substance causing it to flow to the desired form.

Pressing seggars to form is relatively simple. As the side walls of the same are vertical, the plunger die may be readily withdrawn and the seggar easily removed from within the outer die casing. In adapting seggar, or similar presses, to the manufacture 20 of hot tops several novel features must necessarily be added to the press to make the operation practical. This is necessary because hot tops have sloping portions on their outer wall; that is, the outside surface of the hot 25 top spout, which fits into the ingot mold, has an opposite taper from the vertical than the taper of the inside surface of this portion of the hot top. Owing to the double taper which is desirable in many types of hot tops, it has 30 been found impossible to press them with one operation by using a solid outer die casing. Even though the hot tops do not have a double taper they have seat portions or flanges which present a difficulty in the pressing operation similar to that encountered when 35 pressing a double tapered wall.

The object of this invention is to provide a combination of dies which will form a hot top in one pressing thrust of a plunger.

Another object of the invention is to provide dies which may be readily adapted to any press, and which will form a hot top in one reciprocation of the plunger, and leave the hot top so formed that it may readily be 45 removed from the outer die.

In the drawings Figure 1 is an isometric view of a seggar press showing the dies of the present invention attached thereto; Figure 2 is a vertical section through the plunger 50 and dies, showing the same at the start of the

forming operation; Figure 3 shows a similar view of the dies at the end of the forming stroke of the plunger; Figure 4 is another similar view showing the position of the dies and plunger removed from the formed hot 60 top; Figure 5 is a view taken on the line 5—5 of Fig. 4; Figure 6 is a vertical sectional view through a set of dies of a slightly modified structure; Figure 7 is a vertical sectional view of a formed hot top with the pouring 65 hole cut in the top web portion; Figure 8 is a top plan view of a die mold showing a modified loose ring and means for fastening the same; and Figure 9 is a sectional view taken on the line 9—9 of Fig. 8.

In the drawings the reference numeral 1 designates the frame of a press having a sliding bed 2, and a vertical sliding head 3 which carries a top plate 4 to which any plunger or die may be attached.

In Figure 2 the forming parts of the machine are shown in section. An outer die casing 5 fits over a plate 6, which rests on the bed 2 of the press. Loose ring 7 fits into the outer die casing 5, substantially as shown. 80 The edge 8 of the ring serves to form the ridge of the hot top which rests on the top of the ingot mold. As may be noticed, the hot top is formed bottom up, since the inner walls converge toward the top of the same in its upright position. The loose ring 7 is positioned and locked in the casing 5 by means of a plurality of pins 9 which fit into apertures 10 in the said casing 5. A locking ring 11 is placed in the upper edge of casing 5 85 and maintained in its place by means of an annular plate 12. The locking ring 11 has apertures 13 spaced to match apertures 10 in the die casing. When the loose ring 7 is properly positioned, the lock ring 11 may be 90 slightly turned by means of a handle 14 to lock the ring in place. Several reach rods 15 are fixed in the loose ring 7 and pass upwardly through the top plate 4. As the reach rods pass loosely through the top plate the loose ring is not moved by the downward thrust of the plunger 19 from its position as shown in Fig. 2. However, after the plunger 19 has descended on the plastic composition 17, and pressed it into the form of hot top 18,

the lock ring is turned back so that its apertures coincide with apertures 10 of the casing 5. As the top plate 4, carrying plunger die 19, is raised, the nuts 15^a on reach rods 15 engage top plate 4 and the loose ring 7 is 100 105 110

withdrawn, leaving the formed hot top 18 in the casing 5 as shown in Fig. 4. From this position the formed hot top may be readily removed and the dies set for a repeated 5 operation. The method of removal is explained in conjunction with Fig. 9.

Figure 6 shows a slight variation in the die arrangement. The loose ring 20 has the inner wall 20^a tapered. A greater seating 10 ridge may be had, if desired, by sloping the outer wall outwardly for a short distance. The said sloping may be accomplished by bolting a ring 21, having tapered sides 21^a, in the die casing 5.

15 In Figures 8 and 9 a modified form of loose ring is shown. The said ring comprises two sections 25 and 26 which seat in die casing 27 substantially as illustrated. A plurality of pins 28 pass through the die casing 27 and 20 into holes 29 in loose ring sections 25 and 26, and serve as means to lock the said sections in the casing 27. The die casing sets over a plate 6 as in the other forms of dies previously described. After the hot top 30 is 25 pressed into form and the plunger die withdrawn, the sections 25 and 26 are removed. The table 2 may then be slid over a jack plate 31 which is raised by means of a rack and pinion 32 to remove the hot top from the 30 die casing.

The circumferential shape of the hot top is immaterial to this invention since the dies could be shaped to any desired form in cross section. It should be noticed that the plunger 35 does not descend all the way through the material to the plate 6. This leaves a web portion 18^a in the top of the hot top. Opening 18^b may be easily cut or pressed in this web, or the entire web may be removed if so desired.

40 What I claim is:

1. In die construction for the forming of plastic materials the combination of a female forming die, a male forming die, a 45 shaped annulus secured in the female forming die, an annular die member arranged to be seated in the female die and loosely attached to the male die, and means for locking the annular die member in the female die.

50 2. In die construction for the forming of plastic materials the combination of a female forming die, a male forming die, a shaped annulus secured in the female die, and an auxiliary die member removably supported in the female die.

55 3. In die construction for the forming of plastic materials the combination of a female forming die, a male forming die, a shaped annulus secured in the female die, an auxiliary die member removably supported 60 in the female die, and means for locking the auxiliary die member in the female die.

65 4. In die construction for the forming of plastic materials the combination of a female forming die, a male forming die, and

an annular die loosely attached to the male die arranged to be seated in the female die previously to the entry of the male die.

5. In die construction for the forming of plastic materials the combination of a female forming die, a male forming die, an annular die member loosely attached to the male die arranged to be seated in the female die previously to the entry of the male die, and means for locking said annular die member in the female die.

6. In die construction for the forming of plastic materials the combination of a female forming die, a male forming die, and an auxiliary female die member within the female die and loosely attached to the male die.

7. In die construction for the forming of plastic materials the combination of a female forming die, a male forming die, an auxiliary female die member within the female die and loosely attached to the male die, and means for locking the auxiliary die member in the female die.

8. In die construction for the forming of plastic materials the combination of a female forming die, a male forming die, and an annular female die portion arranged to be removably seated in the female forming die before the entry of the male die.

9. In die construction for the forming of plastic materials the combination of a female forming die, a male forming die, an annular female die portion arranged to be seated in the female die, said annular female die portion being loosely attached to the male forming die, and means for locking the annular female die portion in the female die.

10. In die construction for the forming of plastic materials the combination of a female forming die, a male forming die, and an auxiliary female die member removably supported in the female forming die.

11. In die construction for the forming of plastic materials the combination of a female forming die, a male forming die, an auxiliary female die member removably supported in the female forming die and loosely attached to the male forming die, and means for locking the auxiliary die member in the female forming die.

12. In die construction for the forming of plastic materials the combination of a female forming die, a male forming die, a shaped annulus in the female forming die, an auxiliary female die member loosely attached to the male die and arranged to be seated in the female die, lugs on the auxiliary die member, slots in the shaped annulus to receive the lugs, and a locking ring having apertures arranged to be brought in register with the lugs on the annular die member and the slots in the shaped annulus.

13. In die construction for the forming of plastic materials the combination of a fe-

male forming die, a shaped annulus in said die, an auxiliary die member removably supported in the shaped annulus, lugs on the auxiliary die member, notches in the said shaped annulus, and a locking ring having apertures arranged to be brought into register with the aforesaid lugs and notches.

14. In die construction for the forming of plastic materials the combination of a female

forming die, a male forming die, a shaped annulus secured in the female forming die, and an annular die member arranged to be seated in the female die and loosely attached to the male die.

In witness whereof, I hereunto set my hand.

AUSTIN L. MOORE.
